PRESSURE SWITCH

Thomas H. Yarbrough and John Paul Wheat,
Waco, Tex.

Application September 14, 1942, Serial No. 458,280

1 Claim. (Cl. 200—83)

This invention relates to a pressure switch and the primary object of the invention, is the provision of a device which is especially adapted to stop the operation of an internal combustion engine whenever the lubricant pressure falls from some cause or decreases below an amount which would be detrimental to the engine or cause damage thereto should the latter continue to operate when the lubricant pressure is not in sufficient amount.

Another object of this invention is the provision of a device of the above-named character which may be easily and quickly adapted to an engine and its ignition system, whereby the latter will be broken should the lubricant pressure fall from some cause and is of a construction to permit the device to be conveniently adjusted for operation on an engine having a battery ignition system.

With these and other objects in view as will become more apparent as the description proceeds, the invention consists of such novel features of construction, combination and arrangement of parts as will be hereinafter more fully described and claimed.

For a complete understanding of our invention, reference is to be had to the following description and accompanying drawing, in which—

Figure 1 is a vertical sectional view illustrating a pressure switch constructed in accordance with our invention.

Fig. 2 is a sectional view taken on the line 2—2 of Fig. 1.

Fig. 3 is a diagrammatical view illustrating a wiring diagram showing the present invention electrically connected in a battery type ignition system wherein a portion of the latter is shown.

Referring in detail to the drawing, the numeral 5 indicates in its entirety a pressure switch including a base 6 on which is clamped or clinched a casing 7. A diaphragm 8 is located within the casing 7 and is held in position on the base 6 to form a pressure chamber 9 by the clinching of the casing 7 on the base. A threaded nipple 10 is integral with the base 6 and is equipped with a bore 11 extending from end to end thereof and connecting with the pressure chamber 9. The nipple 10 is employed for connecting the pressure switch 5 into a lubricant pressure line of an internal combustion engine so that the pressure of the lubricant within the engine will act on the diaphragm for the purpose of flexing or expanding said diaphragm. As soon as the pressure falls below a predetermined amount or falls the diaphragm returns to its initial position.

A supporting member 12 is secured on the interior of the casing 7 in any well known manner to establish an electrical connection therewith and has threaded thereto a stub bolt 13 employed for mounting on the support 12 a contact member

14 arranged a selected distance from the diaphragm. The contact member 14 adjacent its free end and upon opposite faces thereof is provided with contact points 15 and 16. A pin 17 is secured to the contact member 14 and is engaged by the diaphragm so that when said diaphragm is expanded or flexed by the pressure of lubricant within the pressure chamber 9 the contact member is caused to flex or change from a normal position.

The stud bolt 13 also provides a mounting for a contact member 18 a portion of which parallels the contact member 14 and is spaced therefrom. The contact member 18 includes a hook-shaped portion 19 extending about and spaced from the free end of the contact member 14 and has secured thereto contact points 20 and 21 also an insulating member 22 disposed opposite to an adjusting screw 23. The adjusting screw 23 threads into a bracket 24 a portion of which clamps between the casing and diaphragm and thereby is held in a fixed position. The set screw 23 includes a knurled head 25 positioned under an opening 26 provided in the casing 7. The knurled head is provided with a kerf 27 to be engaged by a screw driver of the like arranged through the opening 26 so that the set screw or adjusting screw may be rotated in either direction. A leaf spring 28 is secured to the bracket 24 and rides against the knurled head for retaining the set screw against accidental rotation. Also a coiled spring 29 may be arranged on the set screw and bears against the head thereof and the bracket to assist in retaining the set screw against accidental rotation. The purpose of the set screw is to adjust the hook-shaped portion 19 of the contact member 18 relative to the contact points on the contact member 14 so as to adapt the use of the pressure switch 5 to either an ignition system of the battery type or magneto type and which will be hereinafter more fully described.

An insulating block 30 is arranged between the contact members 14 and 18 where they are mounted by the lug bolt 13 on the bracket 12. Also an insulating sleeve 31 is provided on the lug bolt 13 to insulate the latter from the contact member 18.

The lug bolt 13 secures on the contact member 18 a contact finger 32 which bears against a terminal 33 mounted on and insulated from the casing 7.

A suitable gasket 34 is provided in the casing to effect a seal between the latter and the base 6 to prevent the switch from losing pressure from the pressure chamber 9.

In Fig. 3 we have illustrated a portion of a battery type ignition system for an internal combustion engine, the battery being indicated by the character 35 one terminal of which is

connected to an electrical ground by a conductor 36. The other terminal thereof is connected to an ammeter 37 by a conductor 38. An ammeter 37 is connected to an electric relay 39 by a conductor 40. A terminal 41 of the relay 39 is connected to an ignition switch 42 by a conductor 43. The ignition switch 42 is electrically connected to the coil 44 of the ignition system by a conductor 45. The coil 44 is connected to the usual distribution (not shown) by the lead 46. A terminal 47 of the relay 39 has a conductor 50 connected thereto and the latter is connected to the ground by a manually operated switch 51. The present invention is electrically connected in the battery type 15 ignition system by having the terminal 33 connected to the conductor 50 by a conductor 52. It is to be understood that the pressure switch 5 by having its nipple 18 threaded into a lubricant pressure line of the engine becomes electrically grounded in the ignition system of said engine.

The relay 39 includes posts 53 and 54 electrically connected to the terminals 41 and 47 and are insulated from each other.

An electro-magnet 55 is included in the construction of the relay and is electrically connected to the terminal 38 and also is electrically connected to the post 54 by a conductor 56. A spring influenced contact arm 57 is pivotally mounted on the post 54 and acts as an armature for the electro-magnet 55, and is adapted to be drawn in engagement with the post 53 when the magnet 55 is energized, the spring of the contact arm acting to disengage said contact arm from the post 53 when the magnet 55 is deenergized. The posts 53 and 54 are capable of conducting electricity. When the ignition switch 42 is closed electric current may flow from the battery through the ammeter, terminal 38 and post 54 to the ground by way of the switch 51 when the latter is closed. As soon as the electro-magnet is energized the contact arm 57 is drawn thereagainst and against the post 53 so that electric current may also flow through the ignition switch to the coil 44.

In adapting the present invention to operate with a battery ignition system of the kind described, the adjusting screw 28 is moved into a position for sustaining the contact points 16 and 18 spaced from the contact elements 20 and 21 when the chamber 9 is free of pressure. This occurs when the engine is idle. When the engine is cranked or started the lubricant pressure is low or near zero and the switch 51 must be closed as well as the ignition switch for the starting of the engine. However, as soon as the lubricant pressure reaches normal under the operation of the engine, the diaphragm expands and moves the contact member 14 so that the contact point 18 engages the contact point 20 connecting the conductor 50 to the ground through the present invention, the switch 51 is then manually open. When the device is operating as described, should the lubricant pressure cease from any cause, the diaphragm will return to its initial position permitting the contact element 14 to assume its normal position disengaging the contact points 15 and 20 interrupting the electric circuit of the magnet 55 so that the latter becomes de-energized and the

contact arm 57 under the influence of its spring then moves into the circuit breaking position, breaking the ignition circuit to the coil 44 de-energizing the latter and consequently stopping the operation of the engine. This will prevent operation of the engine when the lubricant pressure fails and consequently prevents the engine from damaging itself from want of lubricant.

As shown in Fig. 2 the spring 28 has a bifurcated end to straddle and contact the knurled head of the adjusting screw for the purpose of retaining the adjusting screw against accidental rotation. However, the adjusting screw may rotate relative to the bifurcated end when a screw driver is placed in the kerf and rotated.

It will be seen through the use of our invention in the battery type ignition system that if the ignition switch 42 is left closed when the engine is idle, the battery will be prevented from discharging owing to the fact that the pressure switch 5 is in circuit breaking position at this time owing to the fact that it is free of any lubricant pressure. Therefore the present invention provides for automatically stopping the engine should the lubricant pressure fail and also will prevent discharge of the battery when the engine is idle if the ignition switch is left closed.

While we have shown and described the preferred embodiment of our invention, it will be understood that minor changes in the construction, combination, and arrangement of parts may be made without departing from the spirit and scope of the invention as claimed.

Having thus described our invention, what is claimed is:

In an automatic pressure switch for an ignition system of an internal combustion engine, a base, a diaphragm coacting with said base and providing a pressure chamber, a casing clamped to the base for securing the diaphragm to the latter, a threaded nipple formed on the base and connecting the chamber to a lubricant pressure system of an engine and electrically grounding the base to the engine, a contact member mounted in said casing and influenced by said diaphragm, contact points arranged on opposite sides of the contact member, a second contact member mounted in the casing and insulated from the first contact member and having a hook-shaped portion, contact points secured to said hook-shaped portion for coacting with the contact points carried by the first-named contact member, a terminal carried by said casing and adapted to be connected into an ignition system of the engine, a contact finger connecting said terminal to the second mentioned contact member, a bracket mounted in said casing, an adjusting screw carried by said bracket for the adjustment of the second-named contact member relative to the first-named contact member, a spring member carried by the bracket and having a bifurcated portion to engage the adjusting screw for sustaining the latter against accidental movement, said casing having an opening to permit a tool to extend therein to engage the adjusting screw.
